MECHANICAL MOVEMENT.

1,334,784.

Specification of Letters Patent. Patented Mar. 23, 1920.

Application filed November 18, 1918. Serial No. 262,957.

To all whom it may concern:

Be it known that I, WILLIAM J. NEWTON, a citizen of the United States, residing at Bridgeport, county of Fairfield, State of Connecticut, have invented an Improvement in Mechanical Movements, of which the following is a specification.

This invention has for its object to provide a mechanical movement especially adapted for any of the various uses in which an exceedingly quick movement of a part or parts is required, as in operating steam and hydraulic valves, making and breaking electric circuits, etc. This result I accomplish by means of a striker which is caused through the action of a spring controlled toggle joint, or equivalent means, to strike a hammer blow upon a swinging member which I term the actuating member.

20 In the accompanying drawing forming a part of this specification,

Figure 1 is a side elevation illustrating an application of my novel mechanical movement;

25 Fig. 2 an end elevation as seen from the right in Fig. 1;

Fig. 3 a section on an enlarged scale on the line 3-3 in Fig. 2, looking in the direction of the arrows, and

30 Fig. 4 is a sectional view illustrating a variant form of the invention.

10 denotes a frame by which the parts are carried and which is conveniently made U-shape, although the special design of the

35 frame is immaterial so far as the principle of the invention is concerned. The side pieces of the frame are shown as provided with attaching flanges 11 by which it is secured in place. The actuating member is shown

40 as double and consists of side pieces 12 which are pivoted on the outer sides of the side pieces of the frame, and spaced apart projections or cross pieces 13 connecting the lower ends of the side pieces. When an

45 actuating member with a single side piece is used projections of course take the place of cross pieces. 14 denotes the striker, shown as made U-shape, the side pieces of

50 which are pivoted to the inner sides of the side pieces of the frame. In the present instance, the actuating member and the striker are shown as swinging from the same pivots, although it is immaterial whether or not they are pivoted concentrically. In the form

55 illustrated in Figs. 1, 2 and 3, the toggle

joint comprises an operating member 15, which is a lever of the first order and is pivoted between the side pieces of the frame above the pivotal points of the striker and the actuating member, and a toggle arm 16 having a head 17 which is pivotally connected to the inner end of the operating member, the other end of the toggle arm being adapted to slide freely in a hole 18 in the cross piece of the striker. 19 denotes an angle piece, which may or may not be used as preferred, and which rests upon the cross piece of the striker and is provided with a hole corresponding with hole 18. 20 denotes a relatively strong compression spring carried by the toggle arm and bearing against the head of said arm and against the cross piece of the striker or against the angle piece, if used. Washers 21 are preferably interposed between the ends of the spring and the head of the toggle arm and the angle piece, respectively.

The special mechanical connections by which the practically instantaneous movements of the actuating member, caused by the blows of the striker, are utilized in mechanical operations are immaterial so far as the present invention is concerned. I have shown two oscillatory shafts, indicated by 22, which are journaled in suitable bearings 23. Each shaft has extending therefrom a rigid arm 24, said arms being loosely pivoted to ears 25 on the cross pieces of the actuating member.

The operation is as follows: It will be noted that the striker lies between the cross pieces of the actuating member which are spaced apart far enough to give full effect to the blows of the striker. It is wholly immaterial so far as the present invention is concerned whether the operating member is operated mechanically or manually. In either case when the toggle joint is moved toward its dead center the spring will be compressed, the toggle arm sliding freely in the holes in the angle piece and the cross piece of the striker. The lower end of the spring, or the lower washer if used, will ride up an angle of the angle piece until it reaches the apex of the angle piece. An instant later the washer will start to ride down the other angle of the angle piece and the full power of the spring will be exerted instantly to throw the toggle joint to the extreme of its movement opposite to the

starting position. It should be understood, however, that the device is perfectly operative if the angle piece is omitted. The toggle arm of course carries the striker, so the result is, either with or without an angle piece, that the full strength of the spring is exerted upon the striker causing it to strike a violent blow upon the cross piece of the actuating member opposite to the one with which the striker was previously in contact. The operating member remains stationary until it receives the blow and the movement of the actuating member is limited by engagement of one of its cross pieces with the frame. In the present instance the instantaneous movements of the actuating member will be transmitted by means of arms 24 to the shafts and will cause practically instantaneous oscillatory movement of the shafts.

The form illustrated in Fig. 4 differs in that the toggle arm, as an independent element, is dispensed with and another type of spring is used which combines the functions of both toggle arm and spring. The operating member, actuating member, and striker are the same as before. In lieu of the toggle arm and compression spring of the other form, I use a spring comprising one or more coils 26 which lie between the side pieces of the striker and in the plane of movement of the striker, and arms 27 which extend in opposite directions. One of these arms is pivoted to the operating member as at 28, the other arm being pivoted near the free end of the striker, as at 29.

The operation is practically the same as before. The action of the combined spring and toggle arm is to retain the toggle joint bowed and the striker at one extreme or the other of its movement. Manipulation of the operating member will cause distortion of the coils of the spring which will accumulate power until the toggle joint has reached its neutral position or dead center. An instant later the spring will react and its full power will be exerted to throw the toggle joint to the other extreme of its movement, causing the striker to strike a violent blow upon the opposite projection or cross piece of the actuating member and throw said member to the opposite extreme of its movement.

Having thus described my invention, I claim:

1. A mechanical movement comprising a swinging actuating member, a striker adapted to engage opposite sides of the actuating member, and a spring controlled toggle joint acting to retain the striker at its normal position until the joint has been swung past its dead center and to then cause the striker to violently strike the actuating member and throw it to the other extreme of its movement.

2. A mechanical movement comprising a

frame, a swinging actuating member pivoted thereto and having projections which engage the frame to limit their movement, a swinging striker, and means for causing the striker to strike a projection of the operating member and throw the latter to the opposite extreme of its movement. 70

3. A mechanical movement comprising an actuating member, a striker, and a spring controlled toggle joint which causes the 75 striker to strike the actuating member when the joint is swung past its dead center.

4. A mechanical movement comprising a swinging actuating member having projections, a swinging striker between the projections, and a spring controlled toggle joint one member of which has sliding engagement with the striker, whereby the latter is caused to strike a projection of the actuating member and throw the latter to the opposite extreme of its movement when the joint is thrown past its dead center. 80 85

5. A mechanical movement comprising an actuating member having side pieces and spaced apart cross pieces, a swinging striker 90 between the cross pieces, and a spring controlled toggle joint, one member of which has sliding engagement with the striker, substantially as described for the purpose specified. 95

6. A mechanical movement comprising a U-shaped frame, an actuating member comprising side pieces pivoted outside the side pieces of the frame and spaced apart cross pieces, a U-shaped striker pivoted inside 100 the side pieces of the frame and lying between the cross pieces of the actuating member, and a spring controlled toggle joint, one member of which has sliding engagement with the striker. 105

7. A mechanical movement comprising a U-shaped frame, an actuating member comprising side pieces pivoted outside the side pieces of the frame and spaced apart cross pieces, a U-shaped striker pivoted inside the side pieces of the frame and lying between the cross pieces of the actuating member, an operating member, a toggle arm pivoted to the operating member and having sliding connection with the striker, and a compression spring whereby the striker is caused to strike a cross piece of the actuating member and throw said member to the opposite extreme of its movement. 110 115

8. A mechanical movement comprising a 120 shaft having an arm extending therefrom, an actuating member to which said arm is pivotally connected, a striker, and a spring controlled toggle joint which causes the striker to throw the actuating member to 125 the opposite extreme of its movement and thereby impart an oscillatory movement to the shaft.

9. A mechanical movement comprising a 130 swinging actuating member, a swinging U-

shaped striker, an angle piece on the cross piece of the striker, an operating member, a toggle arm having sliding connection with the striker and the angle piece and having 5 a head pivotally connected to the operating member, and a spring bearing against said head and the angle piece respectively.

10. A mechanical movement comprising a swinging actuating member, a striker, an

operating member, a toggle arm having sliding connection with the striker and having a head pivotally connected to the operating member, and a spring bearing against said head and against the striker whereby the latter is caused to throw the actuating member to the opposite extreme of its movement. 15

In testimony whereof I affix my signature.
WILLIAM J. NEWTON.
